P. H. MACK

LETTING-IN TOOL FOR OIL AND GAS WELL APPLIANCES

Filed Jan. 29, 1924

INVENTOR

UNITED STATES PATENT OFFICE.

PATRICK H. MACK, OF BRADFORD, PENNSYLVANIA, ASSIGNOR TO OIL WELL SUPPLY COMPANY, OF PITTSBURGH, PENNSYLVANIA, A CORPORATION OF PENNSYLVANIA.

LETTING-IN TOOL FOR OIL AND GAS WELL APPLIANCES.

Application filed January 29, 1924. Serial No. 689,306.

This invention is for a letting-in tool for use in connection with oil and gas well packers, liner supports and other appliances.

In the setting of liners and packers, it is 5 desirable to lower them into the well, manipulate them to manipulate the expanding supporting devices, and then disconnect and withdraw the letting-in tools. A common practice has been to lower the packer or liner 10 support into the well on a rigid stem made of sections of pipe, and then disconnect the string of pipe from the liner support or packer, and withdraw it.

In my application Serial No. 655,017, filed 15 August 1, 1923, I have disclosed a support for liners or packers which may be set in the well by being lowered with the ordinary string of tools and a cable.

The present invention has for its object to 20 provide a letting-in tool, by means of which a packer or liner support of this type may be lowered into a well from a string of drilling tools, set, and then disconnected from the letting-in tool.

25 A further object of the invention is to provide a letting-in device for this purpose, wherein there is practically no danger of the packer or support becoming detached prematurely, even though it should temporarily 30 become hung in the well or should its downward movement be impeded by a rising current of gas or oil.

The invention may be readily understood 35 by reference to the accompanying drawings, in which:

Fig. 1 represents a sectional view through a liner support, showing the letting-in device embodying my invention applied thereto;

Fig. 2 is a side elevation of the letting-in 40 tool;

Fig. 3 is a transverse section in the plane of line III—III of Fig. 1;

Fig. 4 is a side elevation of a slightly modified form; and

45 Fig. 5 is a side view of a frangible key used in connection with my letting-in tool.

In the drawings, 5 designates the tubular body of a liner support or packer. I have 50 illustrated a liner support, but it will be obvious that the invention would be the same were it applied to a packer, and that, so far as the present invention is concerned, they are equivalent.

Screwed onto the upper threaded end of 55 the body 5 is a collar 6 having a central open-

ing at 7, in which is a shoulder 8. In using my invention, a key 9, shown in elevation in Fig. 5, is laid across the top of the tubular body 5 before the collar 6 is screwed into place. When the collar is then screwed on, this key is confined between the top of body 5 and the shoulder 8. The key is preferably made of brittle iron or steel, and is nicked at its center in the bottom, as indicated at 10, the cross sectional area of the key at this point also being the smallest of any part of the key.

The letting-in tool comprises a bifurcated body 11 having its legs 12 extending downwardly and having a threaded extension 13 at its upper end, by means of which it may be 60 screwed onto the bottom of the usual string of drilling tools. One of the legs carries a transverse key engaging member 14. As shown in the construction illustrated in Figs. 1 to 3 inclusive; this member comprises a bar 75 14 having one end pivoted at 15 and a slot 12^a in one leg of the device. The other end of bar 14 is tapered on its upper side, and projects, when in its horizontal position, into a slot 12^b in the other leg of the device.

The lower end of slot 12^b provides a stop to prevent the bar from moving down below a horizontal position, while both slots 12^a and 12^b are so formed as to permit the bar to swing 85 up into a non-vertical position, as indicated in dotted lines in Fig. 2. In this position, there is just barely room for the legs to be passed down over key 9.

In use, the letting-in tool is passed down 90 into opening 7 of collar 6. The legs straddle key 9, which swings bar 14 upwardly as the letting-in tool is forced down. When the key is above the end of bar 14, the bar, not being movable to a full vertical position, drops back to the horizontal position, because 95 of its being out of balance.

The parts are then in the position shown 100 in Fig. 1, and the packer or liner support may be suspended from the letting-in tool by key 9 and bar 14. When the packer or support has been set, as described for instance in my said co-pending application, and it is desirable to withdraw the letting-in tool, the body 11, together with the heavy string of tools from which it hangs is lifted as far as 105 permitted by the key 9 and bar 14, and then suddenly dropped.

The body 11 at the juncture of the legs with the body is rounded, as at 11^a. When 110 the body 11 and the drilling tools drop, the

legs 12, being of sufficient length to permit of a substantial vertical movement between key 9 and the part 11^a, the rounded part 11^a hits the key 9 at its weakest point above the notch, 5 breaking the key, then disconnecting the letting-in tool and the packer. By reason of surface 11^a being curved, the full force of the blow is directed on one point of the key.

If the packer sticks in the well while being lowered, it is practically impossible for key 10 9 to work around to a point where it might later slide out past bar 14, if the latter, through some cause, such as high gas pressure, should be lifted. In other words, accidental disconnection is practically impossible. Key 9 can also be made sufficiently strong to stand a considerable jar before breaking, so that danger of premature breaking of key 9 is not likely.

20 In the modification shown in Fig. 4, 16 is the body having legs 17 and 18, and having an upper threaded extension 19. Leg 17 is relatively heavy, and has a hook 20 at its lower end, whose bottom face is inclined upwardly 25 toward the outer point of the hook, while the top surface of the hook is inclined downwardly toward the leg which carries it. Leg 18, which does not carry the load, is relatively light and resilient. This leg has a slot 18^a 30 into which the point of hook 20 normally projects. At 21 is the rounded part corresponding to port 11^a of the first construction.

The width of the letting-in tool across the legs is sufficient to enable the leg 18 to spread 35 when the legs are inside hole 7 just enough to enable the hook to be forced down over key 9.

40 The operation of the modified form is similar to that of the first construction. The inclined bottom of the hook facilitates the forcing of the hook over the key. After the letting-in tool is in place, the key is guided in close to leg 17, so that there is no danger of the key forcing the device open.

45 Various other changes may be made in construction within the contemplation of my invention.

What I claim is:

50 1. A letting-in tool for well appliances comprising a body having joint forming means on the upper end thereof, spaced apart legs depending therefrom, and a transverse member at the lower portion of the legs for cooperation with means on the well appliance, and a convexed reinforcement on said body between the upper parts of the legs.

55 2. A letting-in tool for well appliances comprising a body having joint forming means on its upper end, a longitudinal key receiving slot in the lower end, means for normally closing the lower end of the slot, and a frangible key slidably received in the slot, the surface of the body at the upper end of the slot being convexed to provide a striking element for the frangible key.

3. The combination with an appliance for wells having a removable collar at its upper end in which is a shoulder, of a one-piece frangible key on the upper end of the appliance retained in place by said collar, and a 70 letting-in tool comprising a body having a longitudinally bifurcated lower portion inserted in the collar, said key extending through the bifurcation in said body, means for normally closing the bifurcated part at 75 the extreme lower end thereof, said letting-in tool having a limited longitudinal movement with respect to the key by means of such bifurcation, a reinforced convex frangible key striking element on the letting-in tool, and means on the letting-in tool for connecting it to a string of tools.

4. The combination with an appliance for wells having a removable collar at its upper 80 end in which is a shoulder, of a frangible key weakened at its center on the upper end of the appliance retained in place by said collar, and a letting-in tool comprising a body having a longitudinally bifurcated lower portion inserted in the collar, said key extending through the bifurcation in said body, means for normally closing the bifurcated part at 85 the extreme lower end thereof, the body having a reinforced convexed striking portion at the upper end of the bifurcated part thereof at the point above the key, said letting-in tool having a limited longitudinal movement with respect to the key by means of such bifurcation, and means on the letting-in tool for connecting it to a string of tools.

5. In an appliance for wells, a tubular body, a single piece of metal disposed across one end thereof constituting a frangible key, a collar detachably secured on said body and holding the key in place, a letting-in tool having an elongated slot through which the key passes, and means preventing movement of the key downwardly out of said slot, the elongation of the slot enabling the letting-in tool to be dropped so that a part thereof will engage and fracture said key.

6. In an appliance for wells, in combination with a tubular body, a single piece of metal disposed across one end thereof constituting a frangible key, said key having a weakened portion, a collar detachably secured on said body and holding the key in place, a bifurcated letting-in tool having said key disposed transversely in the bifurcation, and means preventing downward movement of the key out of the bifurcation, the letting-in tool at the closed end of the bifurcation and in line with the aforesaid weakened portion being shaped to impart the full force of a blow to said weakened portion, the elongation of the slot enabling the letting-in tool to be dropped to effect the aforesaid blow and thereby fracture said key.

In testimony whereof I affix my signature.
PATRICK H. MACK.
